(57) **CLAIM**

The ornamental design for an energy storage power supply, as shown and described.

DESCRIPTION

FIG. 1 is a front, right and top side perspective view of an energy storage power supply, showing our new design; FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of the portion of FIG. 1 encircled by the dashed rectangle labeled as reference numeral 9; and,

FIG. 10 is an enlarged detail view of the portion of FIG. 2 encircled by the dashed rectangle labeled as reference numeral 10.

The broken lines shown in the drawings represent portions of the energy storage power supply that form no part of the claimed design.

The dot-dash broken lines encircling portions of the energy storage power supply in FIGS. 1 and 2 and illustrated in enlarged views in FIGS. 9 and 10 form no part of the claimed design.

The oblique shading in the drawings depicts the transparency of planes.
